UNITED STATES PATENT OFFICE

136,773

DESIGN FOR A SAFETY RAZOR CASE OR SIMILAR ARTICLE

Philip A. Derham, Rosemont, Pa., assignor to
Armstrong Cork Company, Lancaster, Pa., a
corporation of Pennsylvania

Application September 17, 1943, Serial No. 111,143

Term of patent 14 years

To all whom it may concern:

Be it known that I, Philip A. Derham, a citizen of the United States, residing in Rosemont, county of Montgomery, and Commonwealth of Pennsylvania, have invented a new, original, and ornamental Design for a Safety Razor Case or Similar Article, of which the following is a specification, reference being had to the accompanying drawing, forming a part thereof, and in which

Figure 1 is an isometric view of a safety razor case or similar article showing my new design,

Figure 2 is an end elevation of the case shown in Figure 1,

Figure 3 is a side elevation of the case, and
Figure 4 is a top plan view of the case.

I claim:

The ornamental design for a safety razor case or similar article, substantially as shown.

PHILIP A. DERHAM.
